PRESSURE INDICATOR FOR NUTS OR BOLTS

Filed Aug. 22, 1927

INVENTOR.

Edward C. Baynes
Francis D. Hardisty

ATTORNEY.

UNITED STATES PATENT OFFICE

EDWARD C. BAYNES, OF BIRMINGHAM, MICHIGAN

PRESSURE INDICATOR FOR NUTS OR BOLTS

Application filed August 22, 1927. Serial No. 214,625.

The present invention relates to pressure indicators for nuts or bolt heads and to combined indicators and locks for nuts or bolt heads.

5 Heretofore in bolting together pieces of wood or in bolting wood to metal, in cases where the nut or bolt head is in a countersink, the operator, in tightening such nut or bolt head is unable to tell just when to cease turning it in order to obtain sufficient tightening without crushing the wood below it. Such crushing quite materially impairs the strength of the wood at this point and in narrow strips substantially severs the piece.

10 15 Among the objects of the invention is to obviate this difficulty and provide means by by which the operator may gauge the pressure and determine the point at which the bolt or nut has reached its maximum tightness 20 without materially lessening the strength of the wood piece.

Other objects will readily occur to those skilled in the art upon reference to the following description and accompanying drawings in which:—

25 Fig. 1 is a section through a wood slat showing the usual bolt and washer and how the wood is crushed;

Fig. 2 is a similar section showing the present device;

30 Fig. 3 is a plan view of Fig. 2;

Fig. 4 is a perspective view of the indicator;

Fig. 5 is a longitudinal section therethrough.

35 As indicated in the drawings the present device is designed chiefly for use with countersunk wood members and its main purpose is to prevent conditions indicated in Fig. 1. In this figure a slat or other wood member A is bored as at B and countersunk as at C for the reception of a bolt or screw D and its head E, a washer F usually being placed under the head E. In such constructions, when the bolt or screw D is tightened, the workman screws it down until it admits substantially no further movement, with the result indicated in this figure, namely, the wood X, under the washer becomes crushed and reduces the thickness of the portion having its full strength. If the wood below the countersink

is comparatively thin, it is even possible to break the wood member through and this happens not infrequently.

The present device consists of a thin sheet metal 10 shown as rectangular in shape with its ends 11 bent up at right angles and over in the plane of the main portion, the depth of the device being the same as that of the countersink in which it is to be used. Near the center is a slotted opening 12 for the passage 55 of a bolt and at one side of the hole the device may be cut and provided with the projecting corners 13 and 14 forming a nut locking device such as is set forth in Patent Number 1,617,317 issued February 15, 1927, 60 to the present inventor.

This device is placed in the countersink as shown in Fig. 2 in place of the washer F and when the bolt or screw 15 is tightened serves to indicate when the wood crushing begins, 70 the indication being the lifting of ends 11 toward the full line position of Fig. 2. The workman will then easily recognize that further tightening will crush the wood and impair the strength thereof. The ends 11 may 75 then be flattened to the dotted line position.

As indicated in Fig. 5 the preferred form of the device is slightly bowed upward as shown so that when the nut or bolt head presses down on the part 10, this will flatten 80 out and cause the corners 20 to move laterally and enter the walls of the countersink, holding it firmly against any displacement.

The indicating function of the device does not require the use of the locking tongues 13 85 and 14 but these may be formed and the device, then becomes a nut or bolt locking device as well as a pressure indicator, the tongues functioning in much the same manner as in the patented device.

Having now described the invention and the preferred form of embodiment thereof it is to be understood that the said invention is to be limited, not to the specific details herein set forth but only by the scope of the claims 95 which follow.

I claim:—

1. A combined locking device and pressure indicator for nuts or bolt heads in countersinks in wood members comprising a rectan- 100

gular strip of thin sheet metal perforated for the reception of a bolt, said strip having its ends bent up at right angles and over into the plane of the main portion and being provided with locking tongues at one side of the perforation.

2. A pressure indicator for nuts or bolt heads in countersinks in wood members comprising a resilient strip of metal formed to provide a horizontal bolt-receiving base portion, vertical wing portions, and horizontal end portions, the depth of the wing portions being substantially the same as the depth of the countersinks, as and for the purpose described.

EDWARD C. BAYNES.
